UNITED STATES PATENT OFFICE

2,337,630

HYDROCARBON CONVERSION

Charles L. Thomas, Chicago, Ill., assignor to Universal Oil Products Company, Chicago, Ill., a corporation of Delaware

Application February 28, 1941, Serial No. 380,964

1 Claim. (Cl. 196—52)

This application is a continuation-in-part of my co-pending application, Serial No. 356,596, filed September 13, 1940.

This invention relates to a process for the conversion of hydrocarbon oil into substantial yields of gasoline and more specifically to an improved process combining catalytic with thermal cracking wherein charging oil and selected insufficiently converted hydrocarbons from both thermal and catalytic cracking are subjected to catalytic cracking and the residual portion of the insufficiently converted hydrocarbons from both thermal and catalytic cracking are subjected to thermal cracking.

Catalytic cracking as ordinarily conducted does not employ recycling of insufficiently converted products to the conversion zone because, as has been found, such insufficiently converted hydrocarbons contain a certain amount of undesirable material, the tendency of which is to deposit great amounts of a carbonaceous deposit upon the catalyst particles if recycled to the catalyst zone. This results in a more rapid lowering of the catalyst activity than is encountered when clean unconverted oils are passed in contact with such catalysts. In order to reduce the formation of carbonaceous substances during conversion so that shorter reactivation times and/or lower peak reactivating temperatures may be accomplished, it is usual to pass the hydrocarbon oil in contact with the catalyst only once and then to crack thermally the insufficiently converted oils in a thermal cracking system. In a process employing both thermal and catalytic cracking in the manner above mentioned, the yield and antiknock value of the gasoline product are good but are not as good as one might expect from a process wherein the catalytic recycle is also catalytically cracked.

However, when high boiling petroleum distillates, such as heavy gas oil or wax distillates are catalytically cracked to produce moderate gasoline yields, the insufficiently converted material boiling in the same range as the charging stock is quite amenable to further catalytic cracking since it contains hydrocarbons similar in nature to those of the original charge. On the other hand, the product boiling between the gasoline range and the charging stock range is usually more refractory since it comprises substantially converted materials. If, however, this intermediate boiling product is treated in a thermal cracking operation the fraction of the thermal conversion product boiling approximately in the same range is more suitable for catalytic cracking since many

of the coke forming constituents present in the original fraction have been removed.

Therefore, the object of this invention is to combine a catalytic and a thermal cracking treatment in a novel and useful manner so that the charge to the catalytic treatment comprises a fresh hydrocarbon oil charge, heavy conversion products from the catalytic step, and intermediate insufficiently converted hydrocarbons from the thermal step; and the charge to the thermal treatment comprises intermediate conversion products from the catalytic step and heavy insufficiently converted hydrocarbons from the thermal step.

In one specific embodiment this invention comprises supplying heated fresh charging oil and heated insufficiently converted oils formed as hereinafter set forth to a catalytic conversion zone, fractionating the resultant conversion products to separate gasoline boiling range hydrocarbons, light reflux condensate, and heavy reflux condensate, returning said heavy reflux condensate to said catalytic conversion zone as hereinbefore set forth, supplying said light reflux condensate together with heavy insufficiently converted hydrocarbons formed as hereinafter set forth to a non-catalytic conversion zone, separating the resultant products into non-vaporous liquid residue and vaporous reaction products, fractionating said vaporous reaction products to separate gasoline boiling range hydrocarbons, light insufficiently converted hydrocarbons, and heavy insufficiently converted hydrocarbons, supplying said light insufficiently converted hydrocarbons to said catalytic conversion zone as hereinbefore set forth, and returning said heavy insufficiently converted hydrocarbons to said thermal conversion zone.

The accompanying drawing shows diagrammatically in side elevation one specific arrangement of the apparatus which may be used within the broad scope of this invention.

Referring now to the drawing, fresh charging oil which may comprise any desired petroleum distillate boiling substantially above the gasoline range, preferably heavy gas oil or wax distillate, is introduced through line 1 containing valve 2 into pump 3, line 4 containing valve 5, and is thereafter commingled with insufficiently converted hydrocarbons formed as hereinafter set forth. The resulting mixture is heated to the desired conversion temperature in heating coil 6 disposed in furnace 7, and the heated material is conducted through line 8 containing valve 9 into reactor 10 wherein it is contacted with a catalytic

mass at conditions suitable for converting it to lower boiling range hydrocarbons. The temperature in reactor 10 may range, for example, from 600 to 1200° F., preferably from 800 to 1000° F., and the pressures may range from substantially atmospheric to 200 pounds or more per square inch. Reactor 10 may comprise, for example, a chamber of the heat exchange type to which heat may be supplied or from which heat may be removed by means of a fluid in indirect heat exchange. On the other hand, if desired, reactor 10 may comprise a cylindrical vessel insulated in such a manner that the reactions occurring therein are substantially adiabatic.

Catalysts which have been found to be effective in the catalytic cracking of hydrocarbons may comprise pellets or granules of silica or other siliceous and refractory materials composited with compounds selected from the group consisting of alumina, zirconia, and thoria. In addition, the hydrosilicates of alumina, acid treated clays, or the like, have also been found to be effective in the cracking treatment of hydrocarbons. Although the catalysts above recited are generally considered to be the preferred catalysts their use is not to be construed as a limiting feature, for various other catalysts well known to those in the art may be employed within the broad scope of the invention.

In the catalytic cracking of hydrocarbons relatively large amounts of carbonaceous substances are formed which deposit upon the catalytic material thereby reducing its active surface and necessitating reactivation at periodic frequent intervals. The invention contemplates reactivating the used catalytic material in the usual manner, such as, for example, by passing oxygen-containing reactivating gases in contact with the used catalytic material and removing carbonaceous substances as combustion gases along with the spent reactivating gases. It is desirable, therefore, in order that the operation may be carried out as a continuous process to employ at least two reactors and in some instances more than two reactors so that while the catalytic material in one reactor is being used for effecting conversion of the hydrocarbon reactants the catalytic material in the other or others may be undergoing reactivation.

The reaction products leaving chamber 10 are conducted through line 11 containing valve 12 into fractionator 13 which is operated at substantially the same or at a reduced pressure relative to chamber 10 wherein gasoline boiling range hydrocarbons are separated from higher boiling hydrocarbons. The gasoline hydrocarbons are conducted in the vaporous state through line 14 containing valve 15 and may be thereafter cooled, condensed, and separated from light gases by any well known means, not shown. A portion of the condensed liquid gasoline boiling range hydrocarbons may be returned to fractionator 13 as a cooling and refluxing medium by well known means, not shown, and the remaining portion of the gasoline boiling range hydrocarbons recovered as a product. Heavy reflux condensate which is separated and condensed in fractionator 13 is introduced through line 16 containing valve 17 into pump 18 and line 19 containing valve 20 and is thereafter commingled with the fresh hydrocarbon oil in line 4 as hereinbefore set forth. Light reflux condensate, which is separated and condensed in fractionator 13, is conducted through line 21 containing valve 22 into pump 23 and line 24 containing valve 25, and is there-

after commingled with heavy conversion products formed as hereinafter set forth. The resulting mixture is heated in coil 26 disposed in furnace 27 at a pressure and to a temperature 5 at which substantial cracking occurs, heat being supplied by furnace 27.

The conversion products are directed through line 28 containing valve 29 into communicating reaction chamber 30 wherein further conversion 10 occurs. The temperatures employed in this thermal conversion step may range, for example, from 600 to 1200° F., preferably from 800 to 1000° F., and the pressures may range, for example, from 100 to 1000 pounds or more per square inch. Reaction chamber 30 is preferably insulated to reduce radiation losses therefrom, although no insulation appears in the drawing. The conversion products leaving reaction chamber 20 30 are conducted through line 31 containing valve 32 into vaporizing and separating chamber 33. Chamber 33 is preferably maintained at a pressure and temperature lower than that employed in reaction chamber 30 ranging, for example, from 700 to 1000° F. and from substantially atmospheric to 200 pounds or more per square inch.

In chamber 33 vaporous liquid residue is separated from the vaporous conversion products and is withdrawn through line 34 containing valve 35 30 and may be subjected to any desired further treatment. The vaporous conversion products leaving chamber 33 are conducted through line 36 containing valve 37 into fractionator 38 wherein gasoline boiling range hydrocarbons, intermediate conversion products, and heavy conversion products are separated. The gasoline boiling range hydrocarbons are conducted through line 39 containing valve 40 and are thereafter cooled, condensed, and separated from the gaseous hydrocarbons by any well known means, not shown. A portion of the condensed gasoline boiling range hydrocarbons may be returned to fractionator 38 as a cooling and refluxing medium by well known means, not shown, and the remaining portion is 40 recovered and may be subjected to any further treatment. Intermediate conversion products separated and condensed in fractionator 38 are conducted through line 41 containing valve 42 into pump 43 and line 44 containing valve 45 and 50 are thereafter commingled with the fresh charging oil and with the heavy reflux condensate from the catalytic step as hereinbefore set forth. The heavy conversion products separated and condensed in fractionator 38 are conducted through line 46 containing valve 47 into pump 48 and line 49 containing valve 50 and are thereafter commingled in line 24 with the light reflux condensate from the catalytic conversion step.

An example of one specific operation of the 60 process as it may be accomplished in an apparatus such as that illustrated and described above is approximately as follows: Charging oil comprising a 28° A. P. I. gravity Mid-Continent heavy gas oil is commingled with insufficiently converted hydrocarbons formed as hereinafter set forth and the resulting mixture is contacted with a cracking catalyst comprising substantially silica, alumina and zirconia at a temperature of 900° F. and at a pressure of 30 pounds per square inch. The resulting conversion products are fractionated to separate gasoline boiling range hydrocarbons and light hydrocarbon gases, light reflux condensate, and heavy reflux condensate. The gasoline and light gases are recovered and the heavy reflux condensate is commingled with 70 75

the fresh feed and returned to the catalytic conversion step as hereinbefore set forth. The light reflux condensate together with insufficiently converted hydrocarbons formed as hereinafter set forth is supplied to a thermal cracking step wherein it is maintained at a temperature of 900° F. and at a pressure of 200 pounds per square inch for a sufficient length of time to produce substantial yields of gasoline boiling range hydrocarbons.

The resultant conversion products are supplied to a vaporizing and separating zone maintained at a temperature of 800° F. and at a pressure of 50 pounds per square inch wherein the non-vaporous liquid residue is separated from the vaporous conversion products and is recovered. The vaporous conversion products are supplied to a fractionator wherein gasoline boiling range hydrocarbons and hydrocarbon gases, intermediate conversion products, and heavy conversion products are separated. The gasoline and the hydrocarbon gases are recovered. The intermediate conversion products are commingled with the fresh charging oil and with the heavy reflux condensate from the catalytic conversion step and are subjected to treatment as hereinbefore described. The heavy conversion products are commingled with the light reflux condensate from the catalytic conversion step and are subjected to thermal treatment as hereinbefore described.

In this manner of operation one may obtain a

37.2% yield of 79 octane number gasoline in the catalytic conversion step, a 26.2% yield of 70 octane number gasoline in the thermal conversion step, and a 20.2% yield of residuum from the thermal conversion step, the balance being principally gas, carbonaceous deposits, and loss.

I claim as my invention:

A conversion process which comprises catalytically cracking a relatively heavy hydrocarbon 10 charging oil, fractionating the resultant products to separate therefrom a gasoline distillate, a heavy reflux condensate boiling in substantially the same range as said charging oil and a lighter reflux condensate boiling intermediate said distillate and heavy reflux condensate, returning 15 said heavy reflux condensate to the catalytic cracking step, subjecting said lighter reflux condensate to non-catalytic thermal cracking, fractionating the vaporous products of the thermal cracking independently of the products of the 20 catalytic cracking to separate therefrom a heavy reflux condensate and a lighter reflux condensate amenable to catalytic cracking, returning the last-named heavy reflux condensate to the thermal cracking step, and supplying the last-named lighter reflux condensate to the catalytic cracking 25 step for treatment therein together with the charging oil and the first-mentioned heavy reflux condensate.

CHARLES L. THOMAS.
